Taiwanese Search Report from TW102303182 Dated Jul. 17, 2014.
(Continued)*Primary Examiner* — Susan Hattan*Assistant Examiner* — Charles Hanson(74) *Attorney, Agent, or Firm* — Fitch, Even, Tabin & Flannery LLP**CLAIM**

We claim the ornamental design for a rollator, as shown and described.

DESCRIPTION

FIG. 1 is a front perspective view of a rollator in accordance with our new design;

FIG. 2 is a rear perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines are included for the purpose of illustrating the unclaimed portions of the rollator and form no part of the claim.
